CODED SIGNAL RELAY

Andrew Craig Reynolds, Jr., Waterbury, Conn., assignor to General Time Corporation, New York, N. Y., a corporation of Delaware

Application July 10, 1957, Serial No. 670,955

6 Claims. (Cl. 307—140)

This invention relates to remotely controlled relays and more particularly to a switch actuating relay responsive to a coded signal.

Relays of this type are primarily intended for use in a system which includes a master signal transmitter and a plurality of relays connected to a common power supply line. Each of the relays is adjusted to respond to a particular coded signal pattern and thus the transmitter can selectively actuate any desired relay by sending the proper code on the power line. Systems of this nature have found particular utility when installed on a regular 60 cycle, A.-C. power line with the relays being responsive to high frequency signals superimposed on the line by the transmitter. In this way, appliances receiving power from the line can be remotely controlled from a central station.

One of the major difficulties in setting up a system of the type referred to above is the problem of providing a simple and completely reliable coded signal relay that is immune to spurious transient signals which are found to occur at random in an A.-C. power system. Such transient signals are commonly generated by various forms of heavy duty electrical equipment which may be installed in the system and have abrupt wave fronts comprising many frequency components. Often the spurious signal will include a component having the frequency at which the relays are set to respond and thus a false code is transmitted on the power line which has proven troublesome in such remote control systems.

It is therefore an object to provide a novel coded signal responsive relay which is immune to spurious transient signals and which will operate only upon receiving the proper code signals of sustained duration. It is a collateral object to provide a relay of this character which is simple in design and completely reliable in operation.

In more detail it is an object to provide a relay of the type characterized above which is constructed of conventional cam controlled switches and driven by ordinary timing motors so as to be economical to manufacture. It is a related object to provide such a relay having few parts, and those operating under very light mechanical forces, so that the relay remains reliable and accurate over a long and trouble-free service life.

It is another object to provide a relay of the type referred to above that is simple and convenient to set for response to a particular desired coded signal.

In one of its aspects it is an object of the invention to provide a novel relay of the type discussed above which can supply a controlling current impulse to either of two devices in response to a further code signal transmitted remotely from the central control station.

Other objects and advantages of the invention will become apparent upon reading the attached detailed description and upon reference to the drawings in which:

Figure 1 shows a schematic wiring diagram of a coded signal relay constructed in accordance with the present invention.

2

Fig. 1a shows a typical control station for the relay shown in Fig. 1.

Fig. 2 shows a chart detailing the sequence of switch operation in the relay shown in Fig. 1.

Fig. 3 shows a schematic wiring diagram of a modification of the relay shown in Fig. 1.

Fig. 4 shows a fragmentary perspective view of a time delay device utilized in the relays shown in Figs. 1 and 3.

Fig. 5 is a fragmentary elevation view of the mounting of an adjustable cam on its camshaft.

While the invention will be described in connection with certain preferred embodiments, it will be understood that I do not intend to limit the invention to those embodiments. On the contrary, I intend to cover all alterations, modifications and equivalents as may be included in the spirit and scope of the invention as defined by the appended claims.

Turning first to Fig. 1, there is schematically shown a remotely controlled, switch actuating, relay 10, constructed in accordance with the present invention, connected between a device 11 to be controlled by the relay and the power lines 12, 13 of an A.-C. power system. The A.-C. power system may include a plurality of similarly connected relays, identical to the relay 10, and a high frequency signal transmitter of any conventional type which is effective to superimpose a high frequency signal on the normal 60 cycle A.-C. power system (see Fig. 1a).

In order to detect high frequency signals in the power system and cause the relay 10 to properly respond thereto, a high frequency signal receiver 15 is connected across the lines 12, 13. The receiver 15 may be of any convenient type such as are well known in systems of this nature.

In accordance with the present invention, the relay 10 includes a timing motor which is energized and sealed-in for one operating cycle when the receiver 15 responds to an initiating code signal impulse of predetermined duration, and a second timing motor which is activated under the concurrent control of the first motor and a second, properly timed code signal impulse of predetermined duration for operation of the controlled device 11. In the illustrated embodiment, the first motor 20 is in the form of a self-starting, synchronous motor, of the type commonly employed in electric clocks and other timing devices, which is energized for a single cycle of operation whenever an initiating signal is received by the high frequency signal 15. In order to energize the motor 20 in response to a high frequency signal, the receiver 15 actuates a control relay 21 which closes a set of contacts 22 and completes a circuit, through the normally closed contacts 23, connecting the motor 20 to the A.-C. power system lines 12, 13. The motor 20 is provided with a gear box 25 which rotates a camshaft 26 through a time delay device 30, to which later detailed reference will be made. In the preferred embodiment, the motor 20 and the gear box 25 are effective to rotate the camshaft 26 at an angular speed of 1½ R. P. M.

Since the initiating signal which causes the energization of the control relay 21 and the closing of the contacts 22 lasts only a short time interval, a circuit is provided to seal-in the motor 20 through a complete cycle of operation. This is accomplished by providing a cam 31 fixed to the camshaft 26 which is effective, following the initial energization of the motor 20 and the first rotational movement of the camshaft 26, to close the contacts 32.

This completes a circuit by-passing the contacts 22, 23 and maintains the motor 20 energized until the cam 31 again opens the contacts 32. In the embodiment illustrated, the cam 31 is provided with a single drop-off portion 33 allowing the contacts 32 to open, and, therefore, once the contacts 32 are closed by the cam 31,

they will remain closed for a full revolution of the cam-shaft 26, which is one cycle of operation. Since the shaft 26 rotates at $1\frac{1}{2}$ R. P. M., the cycle of operation for the relay 10 requires a time interval of 50 seconds.

Once the cam-shaft 26 begins rotation and the motor 20 is sealed-in by the circuit through the contacts 32, the contacts 23 are opened to disassociate the circuit controlled by the relay 21 from the motor control circuit. This is accomplished in the present embodiment by fixing a cam 36 to the cam-shaft 26 which is effective to open the contacts 23 when the shaft 26 begins rotating and hold them open until the operating cycle of the motor 20 is completed. This prevents completion of a circuit through the contacts 32 to the remaining circuitry shown in the lower portion of Fig. 1 and described below.

It will be appreciated that when a number of relays similar to the relay 10 are connected to a common A.-C. power system, each will respond in the manner described above when the master transmitter unit imposes an initiated signal onto the common A.-C. power system. In order to select the relay 10 for operation, to the exclusion of other, differently adjusted relays, a second high frequency signal must be transmitted on the lines 12, 13 following the first signal by a particular, selected time interval. In the present embodiment, when a second properly timed signal of predetermined duration is received by the high frequency signal receiver 15, a second timing motor 40 is activated, which in the present instance is a self-starting, synchronous motor similar to the motor 20.

In order to activate the motor 40 only in response to a second coded signal impulse occurring at a selected time during the operating cycle of the motor 20, a positionable timing cam 41 is secured to the cam-shaft 26. The cam 41 carries a single lobe 42 which is effective to operate the contacts 43 only at a selected time during the single revolution of the cam-shaft 26 representing one cycle of relay operation. The second timing motor 40 is energized when the receiver 15 activates the relay 21, in response to a second coded signal impulse, during the same interval in which the lobe 42 is effective to operate the contacts 43. The concurrent operation of the relay 21 and the contacts 43 closes both the contacts 22 and the contacts 43, to complete a circuit from the A.-C. power lines 12, 13 to the second motor 40. The motor 40 is provided with a gear box 45 which rotates a cam-shaft 46 through a time delay device 47 identical to the time delay device 30, and which will be later described in detail. In the preferred embodiment, the motor 40 and the gear box 45 are effective to rotate the cam-shaft 46 at the same angular speed at which the cam-shaft 26 is driven, that is, $1\frac{1}{2}$ R. P. M.

In order to seal-in the motor 40 for operation through a complete cycle, a cam 48 is fixed to the cam-shaft 46 and is effective to close the contacts 49. Thus, when the motor 40 remains energized for a time interval sufficient to rotate the cam-shaft 46 through the time delay device 47, the cam 48 will close the contacts 49. This will complete a circuit bypassing the contacts 43, and will thus maintain the motor 40 energized until the cam 48 completes a single revolution and again opens the contacts 49.

Once the motor 40 is energized and sealed-in, it is effective to transmit the desired current impulse for the control of the device 11. To accomplish this, a control impulse cam 51 is adjustably fixed to the cam-shaft 46 and is provided with a lobe 52 which is effective to close the contacts 53 for a selected interval during the rotational cycle of the second motor 40. Closing the contacts 53 completes a direct circuit from the lines 12, 13 to the device 11. The duration of the current impulse applied to the device 11 will depend upon the dimension of the cam lobe 52, and in practice it has been found desirable to standardize this current impulse interval to either three, five or eight seconds by providing standard cams with suitably shaped cam lobes.

It will be apparent that the device 11 may consist of a visual or audible signal, such as an electric light or bell respectively, or may comprise a latching relay which will be tripped by the current impulse supplied by the relay 10 so as to switch on or off an electrical appliance of any desired type.

It will be understood that the angular position of the cam 41 on the cam-shaft 26 will determine the particular coded signal to which the relay 10 will respond. In order to set the relay for response to any given coded signal, therefore, it is sufficient merely to change the angular relationship of the cam 41 with respect to the cam-shaft 26. To facilitate this adjustment, the cam 41 is loosely mounted adjacent a shoulder 26a formed on the cam-shaft and a nut 55 is threaded on to the cam-shaft (see Fig. 5). The nut may be drawn up to tighten the cam against the shoulder 26a, and thus rigidly fix the adjustable cam in any desired angular position.

Once the second motor 40 has been energized and sealed-in, it will be understood that the current impulse transmitted to the device 11 depends upon the angular position of the cam 51 on the cam-shaft 46. In order to have this current impulse transmitted at a single definite time following the initiation of a coded signal, no matter to what particular code the relay 10 has been set to respond, the cam 51 is adjustably supported on the cam-shaft 46 in a manner identical to the mounting on the cam 41 described above. In this way, the time interval required for the cam 41 to close the contacts 43, in response to a particular code, plus the time interval required for the cam 51 to close the contacts 53, for transmitting the current impulse to the device 11, can always be adjusted to be a constant desired value.

In the illustrated embodiment for example, the cam 41 has been positioned on the cam-shaft 26 so that the contacts 43 are closed thirty seconds following the initial energization of the motor 20. The relay 10 will then respond to a code comprising an initiating signal followed in thirty seconds by a second signal. It is desirable to transmit the current impulse to the device 11 at fifty seconds past the beginning of the coded signal. Since the second signal begins the rotation of the motor 40, the cam 51 must be annularly adjusted on the cam-shaft 46 to close the contacts 53 twenty seconds following the energization and sealing in of the second motor 40. It will be understood then, that the motor 40 will be energized thirty seconds following the initial signal impulse of the code and, twenty seconds following this, the contacts 52 will be closed. Thus, the current impulse to the device 11 will be transmitted fifty seconds following the start of the coded signal. When the relay 10 is adjusted to respond to a somewhat different code, the angular position of the cam 41 must be changed on the cam-shaft 26, and, to keep the operating time of the device 11 constant, the cam 51 is also annularly adjusted on the cam-shaft 46 so that the operating time required to close contacts 43 and the contacts 53 remains a total of fifty seconds.

For the purpose of transmitting a current impulse to the device 11 only when a high frequency signal of predetermined duration is received, and thus prevent operation of the relay 10 by spurious, transient signals, the time delay devices 30 and 47 are provided. As mentioned above, spurious, high-frequency signals are often induced in an A.-C. power system by various electrical devices, these signals being a form of "static" and possessing frequency components within a range which will cause a response from the high-frequency signal receiver 15. Such spurious signals, however, are of short duration and therefore a transient signal received by the high-frequency signal receiver will cause only a momentary activation of the control relay 21, which only briefly closes the contacts 22. By providing the motors 20 and 40 with time delay devices, the brief closings of the contacts 22 caused by spurious, transient signals will be

of insufficient duration to initially seal-in the motor 20 or to later seal-in the motor 40, and thus the relay 10 will be immune to false operating cycles caused by transient signals.

The time delay devices 30 and 47 are identical and therefore it will be convenient to describe only the device 30 in detail, and for this purpose reference will be made to Fig. 4. In the present embodiment, the time delay device 30 comprises a spring-biased, lost motion, driving connection between the output shaft of the motor 20 and the camshaft 26, which is arranged so that when the motor starts rotating, it must first overcome the spring force and take up the lost motion before the cam-shaft 26 is rotated. To provide the lost motion connection, the gear box 25 associated with the motor 20 is connected to drive a disk 60 mounted concentrically with, but independently of, the camshaft 26. The disk 60 rotates the camshaft 26 by means of a pin 61 extending axially of the camshaft through a hole 62 of somewhat greater diameter formed in the cam 31. It can be seen that when the pin is disposed at one edge of the hole 62, the motor 20 must rotate the disk 60 through a distance approximately equal to the diameter of the hole 62 so that the pin 61 may engage the opposite side of the hole and impart a rotational force to the cam 31.

To insure that the disks 60 and the motor 20 are properly "backed off" so that the pin 61 is adjacent the proper edge of the hole 62, a torsion spring 63 is fixed to the camshaft 26 and is tensioned to exert a resilient force against the pin 61 in a direction opposite to that imparted by the motor 20. It can thus be seen that momentary energization of the motor 20, caused by the brief closing of the contacts 22 as a result of spurious, transient signals being picked up by the high frequency signal receiver 15, will only cause the disk 60 to begin revolving and start to carry the pin 61 across the hole 62. Upon the almost immediate deenergization of the motor 20, the torsion spring 63 will return the pin 61, disk 60 and the gear train included within the gear box 25, back to their original starting position. It will be apparent then, that the operation of the relay 10 can be initiated only by energizing the motor 20 for a sustained, predetermined period, which will be the case when a true signal impulse of several seconds duration is transmitted on the A.-C. power system. In a practical case, signal impulses of four seconds' duration for the initial code signal and two seconds' duration for the second signal have been found to be effective.

To hold the camshaft 26 and the cam 31 in their starting positions against the reactive force exerted by the torsion spring 63, the inherent detenting effect provided by the switch actuator for the contacts 32 is utilized. As can be seen in Fig. 4, the contacts 32 are provided with a resilient switch actuator 65 having a detent portion 66 which drops into the notch-like drop-off portion 33 of the cam 31. It will be understood that the engagement of the switch actuator 65 within the drop-off portion 33 will hold the cam 31 and the cam-shaft 26 in their respective starting positions with a detent action. When the motor 20 remains energized for a time sufficient to bring the pin 61 into engagement with the opposite side of the hole 62, the cam 31 will be rotated so as to bring the detent portion 66 of the switch actuator 65 out of the drop-off portion 33 so that the contacts 32 are closed and the operating cycle of the motor 20 initiated.

In order to minimize the resilient force required to be exerted by the torsion spring 63, while insuring that the force is sufficient to "back off" the disk 60 and the gear train in the gear box 25, the motor 20 preferably includes an automatically operating clutch of the type which is commonly employed for such purposes. In clutch motors of this type, the motor armature is automatically engaged with the power output driving train upon energization of the motor winding, and is disen-

gaged upon the deenergization of the motor winding. An example of a motor of this type having such an automatically operating clutch construction can be seen by reference to the United States Patent to Schellens, No. 5 2,234,040, issued November 9, 1943. It will be sufficient for present purposes to observe that the armature in the motor 20 is connected to the driving train in the gear box 25 only when the motor is energized. When the motor is only briefly energized through the action of 10 a spurious signal causing the contacts 22 to flutter momentarily, the gear train in the gear box 25 and the disk 60 are briefly advanced by the motor armature and then completely disconnected from the armature. Thus, the torsion spring 63 need rotate only the disk 60 and 15 the gears within the gear box 25 back to their initial starting positions, and is not required to rotate the entire armature of the motor 20.

The relay 10 can be modified for selectively controlling either one of two devices in response to a third signal impulse in the coded signal. This modification of the invention is shown in Fig. 3, in which a relay 10a is schematically illustrated with the parts similar to those described above having been given the same numerical designation with the distinguishing suffix *a* added. The relay 10a is connected between the power lines 12a, 13a and the two devices to be controlled 71 and 72. A high-frequency signal receiver 15a is connected across the lines 12a, 13a so as to activate a relay 21a in response to a high-frequency signal impulse on the A.-C. control system. As in the operation of the relay 10 discussed above, the initial signal impulse of the coded signal will cause the receiver 15a to actuate the relay 21a and close the contacts 22a to thus complete a circuit through the normally closed contacts 23a and energize the motor 20a. If the motor remains energized during the delay period imposed by the time delay device 30a, the cam 31a will close the contacts 32a and seal-in the motor 20a for a complete cycle of operation.

During the operating cycle of the motor 20a, the cam 41a will close the contacts 43a to energize the second motor 40a if a second, properly timed, signal is received. If the motor 40a remains energized through the time interval imposed by the time delay device 47a, it will seal itself in by means of the cam 48a closing the contacts 49a.

In accordance with a further aspect of the invention, the relay 10a is provided with a double output circuit, one circuit for each of the controlled devices 71, 72, and the control relay 21a is effective to determine which of 50 the output circuits will be conditioned to transmit the desired current impulse for operating one of the devices. In the present embodiment, the control relay 21a is activated and sealed-in as a result of a third signal impulse in the coded signal. This is accomplished by 55 providing a cam 75, fixed to the camshaft 46a, which is effective to close the contacts 76 just before the end of the operating cycle of the relay 10a. If a third signal impulse is received by the receiver 15a during the time interval when the contacts 76 are closed, the activation 60 of the relay 21a will close the contacts 22a and seal-in the control relay by means of the circuit through the contacts 22a and 76. When the control relay 21a is sealed-in the contacts 22a remain closed and thus an output circuit to the device 71 is conditioned. If however, the coded signal does not include a third signal impulse the control relay 21a will not be activated and a set of normally closed contacts 77 under the control of the control relay will remain closed. When the contacts 77 are closed, the second of the two output circuits, 65 which leads to the device 72, will be conditioned.

In order to complete whichever of the two control circuits has been conditioned, two cams 81 and 82 are adjustably mounted on the camshaft 46a and are effective to close the contacts 83, 84, respectively, in the same manner as the cam 51 closes the contacts 53 in the

first described modification shown in Fig. 1. It will be apparent that if the normally closed contacts 77 remain closed because no third signal impulse was included in the coded signal, the closing of the contacts 84 will complete a circuit to the device 72 and thus transmit the desired current impulse to that device. If however, the coded signal includes a properly timed third signal impulse, the control relay 21a will be activated and sealed in so that closing of the contacts 83 by the cam 81 will complete a circuit through the contacts 22a and 83 to transmit the desired current impulse to the device 71.

Résumé of operation

In order to briefly review the operation of the relay 10, reference will be made to the chart shown in Fig. 2, where it can be seen that when the relay 10 is at rest the contacts 23 are closed and the relay ready for operation.

When the first coded signal impulse is detected by the receiver 15, the control relay 21 is actuated and the contacts 22 are closed to complete a circuit energizing the motor 20. The motor 20, upon being continuously energized for the delay period imposed by the device 30, is effective to rotate the cam 31 and close the contacts 32 and thus seal-in the motor 20 for continuous operation throughout a complete cycle, which in this case lasts 50 seconds.

At a certain selected interval during the operating cycle of the motor 20, the cam 41 will be effective to close the contacts 43, and when a second signal impulse of the coded signal is received concurrently with the closing of the contacts 43, the motor 40 will be energized. As was the case with the motor 20, if the motor 40 remains energized through a delay period, it will be effective to rotate the cam 40a and close the contacts 49, sealing in the motor 40 for a complete cycle of operation.

During the operating cycle of the motor 40, it will be effective to rotate the cam 51 so as to close the contacts 53 and complete a direct circuit from the power lines 12, 13 to the device 11 which is to be controlled. In the preferred embodiment the cam 51, as was stated above, has been angularly adjusted on the camshaft 46 so that it will close the contacts 53 at exactly fifty seconds following the start of the coded signal impulse.

It will be apparent that the relay 10 is completely immune to the effects of spurious, transient signals and will not transmit a current impulse to the device 11 in response to a false code made up of a combination of spurious signals. This is due to the operation of the time delay devices 30 and 47. Both the initiating signal required to energize and seal-in the motor 20, and the second timed signal required to energize and seal-in the motor 40, must be of a steady determined duration so that the respective motors can take up the slack in the associated lost motion devices and close the contacts sealing in their operation for a complete cycle. In practice, it has been found that the time delay devices 30, 47 should require a sustained signal duration of approximately two seconds. Since spurious, transient signals are of only fleeting duration, even though they may occur in a series, their resulting intermittent actuation of the relay 21 will not cause the motors 20 and 40 to seal themselves in, and thus the relay 10 remains immune to such false signal patterns.

It will be appreciated that the relay 10 can be economically constructed since it utilizes easily formed cam-controlled switches and conventional timing motors of standard design.

I claim as my invention:

1. A coded signal relay for transmitting a current impulse to a controlled device comprising, in combination, a signal responsive receiver, a constant speed timing motor, means including said receiver for energizing said motor through a complete cycle of operation in response to a signal of predetermined duration, means concurrently

controlled by said receiver and said motor to activate a timing device upon receipt of a second signal at a predetermined selected time during said cycle, output terminals connected to said controlled device and means controlled by said timing device, when activated, to transmit the desired current impulse to said output terminals for operation of said controlled device.

2. A coded signal relay for transmitting a current impulse to a control device comprising, in combination, a signal responsive receiver including a relay actuated when a signal is received, a constant speed timing motor, means including said relay for energizing said motor, means operated by said motor to maintain the energization of the motor through a complete cycle of operation following an initial motor energization period of predetermined duration, means concurrently controlled by said relay and said motor to activate a timing device upon receipt of a second signal at a predetermined selected time during said cycle, output terminals connected to said controlled device and means controlled by said timing device, when activated, to transmit the desired current impulse to said output terminals for operation of said controlled device.

3. A coded signal relay for transmitting a current impulse to a controlled device comprising, in combination, a signal receiver including a relay which is actuated when a signal is received, a constant speed timing motor, means for energizing said motor when said relay is actuated, means for maintaining energization of said motor through a predetermined cycle, a second constant speed timing motor, means controlled by said first motor for energizing said second motor when a second relay actuating signal is received at a selected predetermined time following the start of said cycle, means for maintaining energization of said second motor through a predetermined cycle, output terminals connected to said device, and means operated by said second motor for transmitting a current impulse to said output terminals during its operating cycle for operation of said controlled device.

4. A coded signal relay for transmitting a current impulse to a controlled device comprising, in combination, a signal receiver including a relay which is actuated when a signal is received, a constant speed timing motor, means for energizing said motor when said relay is actuated, means for maintaining energization of said motor through a predetermined cycle following an initial motor energization period of predetermined duration, a second constant speed timing motor, means including a cam controlled switch operated by said first motor for energizing said second motor when a second relay actuating signal is received at a selected predetermined time following the start of said cycle, means for maintaining energization of said second motor through a predetermined cycle following an initial second motor energization period of predetermined duration, output terminals connected to said controlled device, and means operated by said second motor for transmitting a current impulse to said output terminals during its operating cycle for operation of said device.

5. A coded signal relay for selectively transmitting a current impulse to one of two controlled devices comprising, in combination, a signal receiver including a relay which is actuated when a signal is received, a constant speed timing motor, means for energizing said motor when said relay is actuated, means for maintaining energization of said motor through a predetermined cycle, a second constant speed timing motor, means including a cam controlled switch operated by said first motor for energizing said second motor when a second relay actuating signal is received at a selected time following the start of said cycle, means for maintaining energization of said second motor through a predetermined cycle, an output circuit having two alternate sets of output terminals, means operated by said second motor for transmitting a current impulse to said output cir-

cuit during its operating cycle, and means, including said relay activated by said receiver when a signal is received, for directing said current impulse to one set of output terminals when the relay is activated as a result of a third signal for operation of one of said controlled devices and to the other set of output terminals when the relay is not so energized for operation of the other of said controlled devices.

6. A coded signal relay for selectively transmitting a current impulse to one of two controlled devices comprising, in combination, a signal receiver including a relay which is actuated when a signal is received, a constant speed timing motor, means for energizing said motor when said relay is actuated, means for maintaining energization of said motor through a predetermined cycle following an initial motor energization period of predetermined duration, a second constant speed timing motor, means including a cam controlled switch operated by said first motor for energizing said second motor when

a second relay actuating signal is received at a selected predetermined time following the start of said cycle, means for maintaining energization of said second motor through a predetermined cycle following an initial second motor energization period of predetermined duration, an output circuit having two alternate sets of output terminals, means operated by said second motor for transmitting a current impulse to said output circuit during its operating cycle, and means, including said relay activated by said receiver when a signal is received, for directing said current impulse to one set of output terminals when the relay is activated as a result of a third signal for operation of one of said control devices and to the other set of output terminals when the second relay is not so energized for operation of the other of said control devices.
